UNITED STATES PATENT OFFICE

JOSEPH HERMAN SANDELL, OF CHICAGO, ILLINOIS, ASSIGNOR TO COMSTOCK-CASTLE STOVE COMPANY, OF QUINCY, ILLINOIS, A CORPORATION OF ILLINOIS

DESIGN FOR A HEATER DOOR

Application filed January 29, 1930. Serial No. 34,335. Term of patent 14 years.

To all whom it may concern:

Be it known that I, JOSEPH HERMAN SANDELL, a citizen of the United States, residing at Chicago, in the county of Cook and State of Illinois, have invented a new, original, and ornamental Design for a Heater Door, of which the following is a specification, reference being had to the accompanying drawing, forming part thereof.

In the drawing

Fig. 1 is a front view of the heater door showing my new design; and

Fig. 2 is a side edge view thereof.

I claim:

The ornamental design for a heater door, as shown.

JOSEPH HERMAN SANDELL.
